UNITED STATES PATENT OFFICE

EDMUND C. FEY, OF SAN FRANCISCO, CALIFORNIA

AMUSEMENT DEVICE

Application filed November 8, 1926. Serial No. 146,966.

The present invention relates to an amusement device, particularly a game of skill, the playing of which can be entered into by one or two persons.

5 The invention consists primarily in an amusement device or game of skill wherein two characters depicting boxers, fencers or like sportsmen, oppose each other and are under control of the respective players, and 10 are capable of operation to score against their opponent.

In the present invention, the figures are in the form of boxers and are capable of operation and manipulation to be moved into position relative to each other, and their arms capable of operation to alternately present what may be commonly termed a hook-swing and a blocking guard, the characters being further capable of falling from erect to horizontal position on the opponent delivering a 20 blow in a particular manner to a particular portion of the character.

The invention has for its principal object to provide a skill apparatus, wherein two 25 players can, with the aid of characters, carry on a boxing match wherein the skill of the players result in the termination of the match by the character of one of the participants being knocked to the floor by a blow delivered 30 by the character of the other participant.

With other objects in view, which will be presented by the following description, the invention consists in the novel construction and combination of parts hereinafter described, illustrated in the accompanying drawings and pointed out in the claims here- 35 to appended; it being understood that various changes in the form, proportion, size and minor details of construction within the scope 40 of the claims may be resorted to without departing from the spirit or sacrificing any of the advantages of the invention.

In the drawings disclosing the preferred 45 embodiment of the invention—

Fig. 1 is a view in front elevation of a cabinet containing the preferred embodiment of my invention.

Fig. 2 is a view in side elevation of the cabi- 50 net illustrated in Fig. 1.

Fig. 3 is a view in section on line 3—3 of Fig. 5, disclosing the operating handle.

Fig. 4 is a transverse sectional view on line 4—4 of Fig. 5, disclosing more particularly the lower plate and its guides. 55

Fig. 5 is a view in top plan of the character carrying plate, illustrating particularly its shape and the relative arrangement of the parts associated therewith.

Fig. 6 is a view in broken perspective of 60 the character carrying plate illustrating particularly the relation of the operating mechanism positioned beneath the same.

Fig. 7 is a vertical sectional view of the upper portion of one of the characters, illus- 65 trating in front elevation, the arm operating mechanism, and illustrating a portion of the mechanism depending from the head and extending through the body to maintain the character in erect position. 70

Fig. 8 is a view in perspective of the mechanism illustrated in Fig. 7.

Fig. 9 is a view in front elevation of the character, illustrating particularly the angle of the arms extended through the body por- 75 tion.

Fig. 10 is a view in vertical detail section of one of the feet of the character, illustrating an oscillating locking rod connected with the head and engaging under the holding latch, 80 the parts being in standing position.

Fig. 11 is a view similar to Fig. 10, with the character in a horizontal or knocked down position.

Fig. 12 is a view in detail perspective of the 85 character holding rod engaging its holding latch plate.

Fig. 13 is a view in side elevation of the character counter-balancing weight and the operating means connected therewith. 90

Fig. 14 is a view in detail side elevation of the means for locking the characters from movement over the ring surface when the same are in knock-down or prone position.

Referring more particularly to the drawings, wherein like characters of reference designate corresponding parts—the numeral 1 indicates a cabinet having a base portion and a raised portion, the cabinet being preferably hollow and the front of the raised por- 95 100

tion being closed by a transparent member 2, such as glass. The raised portion extending upwardly from the base portion affords a horizontal shelf 3 extending preferably the full width of the cabinet. In rear of the glass 2 the cabinet is provided with a floor and over the same is roped off an area depicting a ring of the type in which boxing matches are conducted, the latter being indicated by the numeral 4.

10 In the ring are positioned two boxing characters 5, the same having movable arms 6 and 7, one of which is bent at the elbow and is normally disposed with the forearm in substantially horizontal position in advance of the chest and the other is substantially outstretched with a slight crook to the elbow. The arms are mounted to alternately raise and lower, as hereinafter described, and for purposes of the present description, the arm 6 may be termed the knockout blow delivering arm, and the arm 7 the guarding or blocking arm. The arms of the respective characters, it will be observed, are reversed relative to each other when the characters are facing one another, as in the drawing. Each character has an axially rotatable head 8 from which extends through the body an axially rotatable rod 9, the same having a lateral extension 10, with the end of which are connected the ends of springs 11 attached to the inner surface of the body, the tendency of which is to maintain the face of the head forwardly or in front position at all times. The lower portion of the rod 9 is hooked at 12, Figs. 10 and 12, to normally extend through the opening 13 in a latch plate 14 and to extend beneath the edge thereof to retain the character in vertical or upstanding position.

40 Each of the characters pivotally supports the arms 6 and 7 on a shaft 15 disposed transversely within the body and the arms extend therefrom and operate through the respective diverging guide slots 16 in the front of the character.

50 An operating means connects with the respective arms and the same consists of a frame 17 pivotally connected with the arm 6, forwardly of the shaft 15, and pivotally connected with the arm 7 at a point 18 rearwardly of the shaft 15. From the frame 17 depends a rod 19, the same extending parallel therewith and terminating at a point adjacent the end of the rod 9, said rod 19 adapted 55 to overlie an operating finger 20 on the end of a shaft 21, axially rotatable by the following described mechanism.

60 Each of the characters is mounted in a like manner and is controlled by a like mechanism, therefore the description and operation of one supporting and operating structure is thought to be sufficient.

65 The shaft 21 extends longitudinally of and forms the pintle of a hinge barrel 22, the supporting flange 23 of which extends parallel

with and is secured to the lateral leg 24 of the supporting plate 25, which is slidable over and supported by the surface of the shelf 3. The leg 24 of the plate is adapted to extend beneath the transparent closure 2 and the body 26 of the plate is adapted to overlie the shelf 3, as in Figs. 1 and 2.

Laterally from the hinge barrel 22 extends a supporting plate 27 to which are attached the feet of the character as indicated in Figs. 1, 5, 10 and 11, and said plate is provided with an opening 28 through which extends the lower hooked end 12 of the member 9—Fig. 11. In this opening 28 also projects, when the plate is in substantially horizontal position—Fig. 10, the operating finger 20 of the shaft 21.

When the character is in upright or standing position, Figs. 1 and 10, a vertical reciprocation of the rod 19 will cause an alternate simultaneous operation or swinging of the arms 6 and 7, and such swinging is accomplished by the following power mechanism.

To the underside of the body 26 of plate 25 is mounted for oscillation a shaft 29 connected through a link 30 and lever 31 with the end of the shaft 21, the shaft 29 carrying a second lever 32 which connects at its end with an operating pin 33 reciprocably mounted within a hand piece 34 extending upwardly from the upper surface of the body portion 26 of the plate 25, Figs. 3 and 6 of the drawing. The surface of the body 26 of plate 25 at either side of the base of the handle 34 is provided with parallel slots 35 through which extend guide bolts 36 secured to a sub-plate 37. The sub-plate is provided with slots 38 disposed at right angles to the slots 35 and in said slots operate guide bolts 39 secured to the wall 40, forming the shelf 3, as in Figs. 3 and 4 of the drawings. The sub-plate 37 and wall 40 beneath the handle 34 are provided with registering cutout portions 41, as in Figs. 3 to 5 of the drawings.

The construction and arrangement of the slots 35 and 38 is such as to permit the player when grasping handle 34 to move the plate 25 in the direction of the slots 35 and 38, the limit of movement being controlled by the bolts 36 and 39.

With the characters arranged opposing each other, as in Fig. 1, it will be apparent that the two players by moving the handles 34 of the respective plates 25 may move the characters laterally across the path of each other and toward each other to a point where the forward edges A of the legs 24 contact, this contacting limiting the relative forward movement of the characters. Thus the players are enabled to move their characters relative to each other in an endeavor to obtain a position of advantage, and during such movement the player, preferably with his thumb, rapidly presses the operating pin or plunger 33, which through its associated

mechanism, causes the swinging of the arms 6 and 7 of the respective characters.

Should one player gain an advantageous position of his character over the other and 5 operate the character arms so that the arm 6 strikes a blow of sufficient strength to turn the head 8 of the other character, such head turning of the other character will cause an axial rotation of the rod 9 and will move 10 the hooked end 12 thereof from beneath the latch plate 14, at which time the character will be free to fall from vertical position, Fig. 10 to horizontal position, Fig. 11.

To insure the dropping of the character 15 when the hook 12 is released from the latch plate 14, a counter-balancing weight 42 is suspended from an arm 43, extending rearwardly of the hinge barrel 22, the weight 42 being sufficient to over-balance the character 20 immediately on the latch 12 disengaging from the latch plate 14. After such action, which in the present game may be termed the knock-out of one of the principals or participants, the prone character is restored to vertical 25 position by the following mechanism.

The weight 42 when the same drops is adapted to rest on a vertically movable base 44, which is adapted for raising, by the operation of a lever 45 extending exteriorly 30 of the cabinet 1, such elevating of the weight 42 causing the movement of the plate 27 from vertical to horizontal position, and will enable the hook end 12 of rod 9 to engage beneath its latch plate 14.

35 To lock the character from needless movement when the same is lying in a prone position, the following mechanism is provided.

To a bracket 46 depending beneath the body 26 of plate 25 is pivotally mounted a 40 lever 47 carrying at one end an upstanding locking pin 48 adapted to register and be received within one of the series of depressions 49 in the plate 37. The locking pin 48 is normally drawn toward the depressions 49 by spring 50. The lever 47 on the end of 45 a lateral extension 51 carries an anti-friction roller 52 adapted to contact with the upper surface of the plate 44, as illustrated in Fig. 6, thus when the plate is elevated to restore 50 the character from prone to vertical position, the plate contacts with the roller 52 and operates the lever 47 to withdraw the locking pin 48 from its associated recess 49. With the locking pin 48 withdrawn from 55 its associated recess, a locking pawl 53 carried by the bracket 46 engages a lateral extension 54 on lever 47 and retains the lever in disengaged or released position. The latch 53 is adapted for operation for disengagement 60 from the extension 54 through the medium of a flexible connection 55, connected at one end with the latch and at its opposite end with the member 22, as illustrated in Figs. 6 and 14. Thus when the character 65 drops from vertical to prone position, the

latch 53 is released and the action of spring 51 will move pin 48 toward one of the recesses 49, the pin entering the recess should the player attempt to impart movement to the plate. The lever 47 also carries a forked arm 56 adapted when the pin 48 is received in one of the depressions 49 to lie beneath and engage an arm 57 extending laterally from the oscillating shaft 29. This engagement will cause the oscillation of the shaft 29 to 70 depress the pin 33 in the handle 34 and retain the same therein, preventing its operation during such time as the character is again restored, as previously described, to 75 vertical position.

I claim:—

1. A game apparatus comprising a pair of contesting characters independently movable to and from and transversely across each other in upright opposing relation, each character mounted for pivotal movement on a horizontal axis and provided with a movable area indicating a vulnerable spot, each character further provided with an arm adapted for movement to attack the movable area of its opponent, means adapted for releasably retaining the characters in upright position and adapted on the actuation of the movable area for releasing the character to permit its pivotal movement to a substantially horizontal 90 position, means for operating the arms of the contesting characters, and means for moving the contesting characters to and from and transversely across in front of each other 95 without affecting the operation of the arms. 100

2. A game apparatus comprising a pair of contesting characters independently movable to and from and transversely across each other in upright opposing relation, each character mounted for pivotal movement on a horizontal axis and provided with a movable area indicating a vulnerable spot, each character further provided with an arm adapted for movement to attack the movable area of its opponent, means adapted for releasably retaining the characters in upright position and adapted on the actuation of the movable area for releasing the character to permit its pivotal movement to a substantially horizontal prone position, and means for operating the arms of the contesting characters independently of their relative movement in upright opposing relation to and from and transversely across each other. 110 115

3. A game apparatus comprising a pair of independent supports movable to and from and transversely across each other in substantially the same horizontal plane, means carried by the respective supports for moving the same to and from and transversely across each other, a contesting character carried normally in upright position on each support and adapted on the relative movement of the supports to oppose each other in contesting position, each character at its base mounted 120 125 130

- on its support for pivotal movement on a horizontal axis and provided with a movable area indicative of a vulnerable spot, each character further provided with an arm 5 adapted for movement to attack the movable area of the opposing character, means for releasably retaining the characters in upright position on their respective supports and adapted on the actuation of the movable area 10 of its character for releasing the character to permit its pivotal movement to a substantially horizontal position, and means carried by the respective supports for operating the arm of its associated contesting character.
- 15 4. A game apparatus comprising a pair of oppositely disposed independently movable contesting characters, each character mounted for independent pivotal movement on a horizontal axis and provided with a movable area, each character further provided with a pair of arms pivotally mounted for unitary operation, one of said arms formed to protect the movable area of its associated character and the other arm formed to strike the movable area of the opposing character, means associated with each character and operatively connected with its pair of arms for actuation to simultaneously operate said arms, means for releasably retaining the respective characters in upright position and adapted on the actuation of the movable area of its character to release the same and permit its movement to substantially horizontal position, and a character manipulating hand grip associated 30 with each character for operation to move its character relatively to its contestant, said hand grip mounting the arm manipulating means of its associated character.
- 35 5. A game apparatus comprising a pair of oppositely disposed independently movable contesting characters, each character mounted for independent pivotal movement on a horizontal axis and provided with a movable area, each character further provided with a pair of pivotally mounted arms adapted for unitary operation, one to protect the movable area of its associated character and the other to strike the movable area of the opposing character, means for releasably retaining the 40 respective characters in upright position and adapted on the actuation of the movable area of its character to release the same and permit its movement to substantially horizontal position, means for locking the characters 45 when in substantially horizontal position from further relative independent movement, means for operating the arms of the contesting characters, and means for restoring the characters from horizontal to vertical position and for releasing said locking means.
- 50 6. A game apparatus comprising contesting characters, independently movable in normally upright opposing relation, one mounted for pivotal movement on a horizontal axis and provided with a movable area

adapted for operation to release the character for movement on its horizontal axis and one provided with a movable member adapted solely to attack the movable area of its contestant, the other of the characters provided with a movable member adapted to solely defend its movable area against the attack of its contestant, means for independently operating the movable members of the respective characters and means for moving the characters in contesting relation, said means mounting the operating means for the movable member of its associated character.

70 7. A game apparatus comprising a plurality of contesting characters, one mounted for pivotal movement on a horizontal axis and provided with a movable area adapted for operation to release the character for movement on its horizontal axis, means for independently mounting the respective characters, whereby the same are relatively movable in upright opposing relation to and from and transversely in front of each other, one of said characters provided with means for solely attacking the movable area of the other character to cause the same to pivot on its horizontal axis, means for relatively moving the characters from side to side and forward and backward, and means for restoring the pivotally mounted character from 75 horizontal to vertical position.

8. A game apparatus comprising a pair of characters, one mounted at its base for pivotal movement on a horizontal axis and one movable to and from and transversely across in front of the other, one of said characters provided with a member adapted for movement independently of the character to contact with its contestant, means adapted for releasably retaining the pivotally mounted character in upright position, said means adapted for releasing to permit the character to pivot to a substantially horizontal prone position upon contact of said movable member with said releasable retaining means, and means for operating said movable member and means for locking one of said characters from movement relatively to the other on the pivoting of said character to horizontal prone position.

100 9. A game apparatus comprising a pair of contesting characters independently movable bodily back and forth and across each other in upright opposing relation, each character mounted for pivotal movement on a horizontal axis and provided with a movable head portion constituting a vulnerable spot, each character further provided with an arm adapted for movement to attack the vulnerable spot of its opponent, means for releasably retaining the characters in upright position and adapted on its actuation by the arm of the opposing character for releasing the character to permit its pivotal movement to a substantially horizontal prone

- position, finger operated means associated with each character for operating it arm, a hand grip associated with each character for moving the character back and forth and across the other in upright position, said hand grip mounting the character arm operating means, a transparent case enclosing the characters, said hand grip and finger operating means being disposed exteriorly of the case.
10. A game apparatus comprising a transparent case, a pair of contesting characters housed therein and visible therethrough, said characters independently movable bodily relatively to each other in upright opposing relation, each character mounted for pivotal movement to a substantially horizontal position and each provided with an arm adapted for movement to attack its opponent and cause its pivotal movement to said substantially horizontal position, means associated with each character extending exteriorly of the case and adapted for operating its arm, a hand grip associated with each character and extending exteriorly of the case for moving the character independently of and relatively to its opponent in upright position, and finger actuated means carried by the hand grip means for operating the arm operating means.
15. A game apparatus comprising a transparent case, a pair of contesting characters housed therein and visible therethrough, said characters independently movable bodily relatively to each other in upright opposing relation, each character mounted for pivotal movement to a substantially horizontal position and each provided with an arm adapted for movement to attack its opponent and cause its pivotal movement to said substantially horizontal position, hand pieces one connected with each character and each located exteriorly of the case for movement to operate said characters relatively to each other in opposing upright position, and means associated with each hand piece and capable of operation independently of the movement of its associated hand piece to operate the arm of its associated character.
20. A game apparatus comprising a transparent case, a pair of contesting characters housed therein and visible therethrough, said characters being independently movable bodily to and from and across each other in upright opposing relation and movable into defeat indicating position, each character provided with an arm movable to attack its opponent and cause its movement from upright to defeat indicating position, a hand piece connected with each character and located exteriorly of the case for movement to independently operate said characters to and from and across each other in opposing relation, and means independently of the hand piece for restoring the characters from defeat indicating position to upright opposing relation.
25. A game apparatus comprising a transparent case, a pair of contesting characters housed therein and visible therethrough, said characters being independently movable bodily relatively to each other in upright opposing relation and movable into defeat indicating position, each character provided with an arm movable to attack its opponent and cause its movement from upright to defeat indicating position, a handpiece connected with each character and located exteriorly of the case for movement to independently operate said characters relatively to each other in opposing relation, and means associated with each character and extending to and carried by the handpiece for operating its arm.
30. A game apparatus comprising a transparent case, a pair of contesting characters housed therein and visible therethrough, said characters being independently movable bodily relatively to each other in upright opposing relation and movable into defeat indicating position, each character provided with an arm movable to attack its opponent and cause its movement from upright to defeat indicating position, a handpiece connected with each character and located exteriorly of the case for movement to independently operate said characters relatively to each other in opposing relation, means associated with each character and extending to and carried by the handpiece for operating its arm, and means independent of the handpiece for restoring the characters from defeat indicating position to upright opposing relation.
35. A game apparatus comprising a transparent case, a pair of contesting characters housed therein and visible therethrough, said characters being independently movable bodily relatively to each other in upright opposing relation and movable into defeat indicating position, each character provided with an arm movable to attack its opponent and cause its movement from upright to defeat indicating position, a handpiece connected with each character and located exteriorly of the case for movement to independently operate said characters relatively to each other in opposing relation, means associated with each character and extending to and carried by the handpiece for operating its arm, and means independent of the handpiece for restoring the characters from defeat indicating position to upright opposing relation.
40. In testimony whereof I have signed my name to this specification.
- EDMUND C. FEY.
